WILBUR L. HOUSEMAN, OF PHILADELPHIA, PENNSYLVANIA, ASSIGNOR TO STAND-
ARD MACHINE COMPANY, OF PHILADELPHIA, PENNSYLVANIA, A CORPORATION
OF PENNSYLVANIA.

PROCESS AND MECHANISM FOR TOPPING HOSIERY.

Application filed May 9, 1922. Serial No. 559,634.

To all whom it may concern:

Be it known that I, WILBUR L. HOUSEMAN, a citizen of the United States, residing at Philadelphia, county of Philadelphia, 5 and State of Pennsylvania, have invented a new and useful Improvement in Processes and Mechanism for Topping Hosiery, of which the following is a full, clear, and exact description, reference being had to the accompanying drawings, which form a part 10 of this specification.

This invention relates to an improvement in the knitting art and more specifically relates to the art of topping hosiery.

15 In the manufacture of socks or half hose having a ribbed top and plain leg, heel, foot and toe portions, the tops are knit in a continuous manner on a ribbing machine and severed from each other. The tops are then 20 positioned on topping or transfer rings and are transferred therefrom to the needles of a circular machine for making plain fabric and the stockings are completed thereon with the exception of looping the toe.

25 Heretofore a large percentage of hosiery of this type, and particularly hosiery of fine gage and hosiery knit on the smaller diameter machines, were thrown out as menders or seconds, due to imperfect loops

30 formed by the first needles thrown into action on the plain machine, or the first plain loops formed at the junction of the cuff and leg portions of the hose. This is caused by either forming the first loops too loose or

35 too tight. If too loose, the fabric at this point will appear as if stitches were dropped or the loops cut, and if too tight the loops will in some cases, be cut when the needles pass therethrough or will be so weakened

40 by being strained during the passage of the needle that they will be broken under a slight strain.

The hosiery knitting machines of today are provided with various yarn carriers to 45 supply different yarns to different portions of the stockings. These yarn carriers are thrown into and out of action at predetermined times by means of pattern mechanism. The ends of the various yarns which 50 are held out of action by their yarn carriers are fixedly clamped so that the yarn between the carriers and clamp is taut so as to enable

the yarns to be thrown into the needles at substantially predetermined points by their carriers.

When making half hose or machines such as shown in Houseman Patents No. 1,204,445, dated November 14, 1916, and No. 1,206,848, dated December 5, 1916, the latch ring, yarn clamp, etc., are thrown out of 55 operative relation to the needles and the needles are moved to a level at which the ends of their latches are below the sinkers. The transfer ring is then placed in position on the needles and the loops are transferred from the points on the ring to the 60 needles. The transfer ring is then removed, the latch ring thrown down and the knitting machine is then set into operation. When the machine is set into operation the 65 needle cylinder together with its needles are rotated for a short period without reciprocating the needles. The stitch and raising cams, together with the yarn carrier, are then thrown into action at predetermined 70 times by the pattern mechanism and during the time the short butt needles or the needles for forming the heel and toe are passing the raising cam, these butts will prevent the raising and stitch cams from being 75 moved radially to their extreme positions, or the positions to reciprocate the short butt needles. As the butts of the long butt needles pass over the raising cam, said 80 needles will first be raised to clear their latches of the loops (of the top transferred thereto) and take the yarn which is thrown into action a plurality of needles in advance of the long butt needles, and the yarn is caught by the hooks of the long butt 85 needles and drawn through the loops of the cuff by the stitch cam. When the cylinder and needles have been rotated a sufficient distance to move the butts of the short butt needles beyond the raising and stitch cams, 90 said cams will be shifted into their extreme knitting positions by their springs, so as to be positioned to actuate the short butt needles when said needles reach the cams. The leg, heel, foot and toe of the stocking 95 are now knit and after a sufficient number of rounds have been knit for the looper, the yarn carrier is thrown out of action and the yarn is clamped and cut. This throwing

out of action of the yarn will cast off the finished stocking and the machine is then automatically stopped.

As before stated, the yarn is thrown into action shortly before the first long butt needle reaches the yarn carrier, and if the yarn is not thrown in on the proper short butt needle, the first loop made by the long butt needle will be imperfect.

Attempts have been made to feed the yarn to the machine between two predetermined needles in advance of the first needle to knit (the first long butt needle), and if the yarn could be controlled to such a nicety, fairly good results would follow. When this problem is fairly studied, it will be appreciated that so many varying factors enter into the problem that it will appear to be impossible to insure the feed of the yarn between two predetermined needles. Some of these factors may be enumerated as follows:

(1) Different conditions will arise with different yarns.

(2) Tension on the yarn.

(3) Tension of the belt which will cause variations in the pick-up of speed when the machine is started. If the belt is tight and the speed is high, the yarn will be thrown in later than if running at a slower speed with a loose belt.

(4) Air currents bowing the yarn between the clamp and carrier.

(5) Condition of the two predetermined needles between which it is desired to cast the yarn relative to the axis of the cylinder. If the first needle is bent either laterally in a reverse direction to the rotation of the cylinder or backwardly toward the axis of the cylinder, said needle is liable to take the yarn instead of passing it; or if the other needle is bent laterally toward the first needle or forwardly away from the axis of the cylinder, it is liable to miss the yarn instead of receiving it.

It will, therefore, be seen that it would be practically impossible to overcome this problem by attempting to cast the yarn between predetermined needles at the beginning of the knitting.

I attempted to solve the problem, in this manner, by various adjustments to attempt to control the casting of the yarn, but was unable to definitely control the cast, which I considered due to the above mentioned uncontrollable factors or others unknown to me.

I found that if the yard were cast between the third and fourth needles in advance of the first needle to knit (the first long butt needle), the best results could be obtained. If, however, it was cast later, for instance, between the second and third, a loose stitch would be formed in the first knitting needle, due to the stitch not being drawn tightly

about the needle. If, however, it was cast sooner, for instance, between the fourth and fifth or fifth and sixth needles, the stitch would be cut by the first needle to knit due to abnormal strain on the yarn.

I then considered and tried other ways of solving this problem and finally discovered a simple solution whereby I could deliver the yarn to the first needle to knit under the same conditions that yarn is delivered to the remainder of the needles, and as the yarn for the first loop is delivered to its forming needle under the same conditions as the yarn for the other loops, it follows that the loops will all be of substantially the same size.

Moreover, it is not essential to cast the yarn between any predetermined needles, it being practical to cast it between any two needles without any abnormal strain being placed on the yarn when the stitch is being formed by the first knitting needle.

This is accomplished, in the way illustrated in the accompanying drawings, by delivering yarn to the hook or hooks of one or a number of needles, as, for example, three, without raising the needles to free the latches from the loops thereon, passing the butts of said needles under the stitch cam to draw yarn from the supply without drawing the yarn through the loops to form new loops, and raising the following needles to free the latches from the loops so that the yarn caught by the hooks thereof will be drawn through the loops thereon to form new loops. Assuming that yarn was fed to the hooks of three needles which were lowered by the stitch cam without first clearing the latches of the loops thereon, the first loop formed would be on the fourth needle, the yarn for forming this loop being subjected to the same conditions as the loops formed by the following needles, that is, drawn from the needles at one side which had previously drawn yarn and passed under the stitch cams, and drawn from the supply at the other side. As the yarn fed to the needle which forms the first loop is subjected to the same tension on both sides of said needle as the yarn fed to the needles for the other loops, it follows that the first loops formed will be the same size as the other loops.

As before described, the yarn fed to the hooks of the first three needles does not form loops on the first round, but clears the latches of said needles when the said needles are raised on the next round and in the majority of cases the yarn fed is knit in as tuck stitches by said needles on their next downward movement under the stitch cam. This not only assures the proper yarn tension for forming the first loop, but knits in by means of tuck stitches at least a portion of the beginning of the yarn in ad-

vance of the first stitch, which will prevent this end of the yarn from pulling out or the stitch from loosening.

In order to manipulate the yarn by the needles, as above described, I shorten the butts of the first three long butt needles. The length of the butts of these three needles is less than the long butts, but greater than the short butts. When the machine is set into motion after transferring the top thereto, the cams are released so as to be moved radially toward the needle cylinder before the medium length butts are in front of the raising cam and before the long butts reach said cam.

The raising cam is moved in radially beyond the ends of the long butts, but not far enough to engage the medium butts, so the long butt needles will be raised to clear their latches of the loops. Shortly after the medium butt needles pass the raising cam, the raising and stitch cams will be released so that their springs are free to act to move said cams radially to their normal knitting positions.

The stitch cam, however, which is back of the raising cam, will be moved into engagement with the ends of the short butts so that the three medium butt needles will be drawn down by the stitch cam to draw yarn from the supply by the three medium butt needles before the first loop of the plain fabric is drawn through a loop of the top which was transferred to the needles. As soon as the raising cam is released after it has been passed by the three medium butt needles, said cam will be shifted by its spring to its position for actuating all of the needles, and as soon as all the short butts have passed the stitch cam, said stitch cam will be shifted to its position for actuating all needles.

The precise nature of my invention will best be understood by reference to the drawings, which will now be described, it being premised, however, that changes may be made without departing from the spirit and scope of my invention as defined in the appended machine claims; it being also understood that the process herein described and claimed is not dependent for its operation upon any particular mechanism.

Fig. 1 is a plan view of a portion of a knitting machine head.

Fig. 2 is a sectional view thereof.

Fig. 3 is a face view of the needle actuating cams.

Fig. 4 is a side view of three needles in three different horizontal planes.

Figs. 5, 6 and 7 are diagrams illustrating the three different positions of the raising cam.

Fig. 8 is a face view of a portion of the needles, illustrating the manipulation of the

yarn and needles at the beginning of the first round of knitting.

Fig. 9 is a similar view on an enlarged scale.

Fig. 10 is a view similar to Fig. 8, but in which the action of the needles is somewhat in advance of that shown in Fig. 8.

Fig. 11 is a perspective view of two needles, having different length latches, which may be used for carrying out my invention, in place of needles having different length butts.

Figs. 12 and 13 are face and plan views, respectively, of cams for raising the needles, when needles having different length latches are used.

In these drawings, *a* designates the needle cylinder which is rotatably mounted in a base *b* and which is rotated and oscillated in the usual manner. Mounted for rotation on the base *b* is a cam disc *d* to which are secured control cams, for actuating the various devices which are shifted in proper sequence during the knitting of stockings. This disc *d* is moved step by step in the usual manner, and the movement thereof is in turn controlled by the well known pattern chain mechanism, not illustrated herein.

Supported on the top of the base *b* is a cam ring *f* having surfaces *g*, *g*, *g*, in the same horizontal plane, see Fig. 3. This ring is provided with the usual inclined surfaces *h*', *h*², *h*³ and *h*⁴. *j* and *k* are guard or top cams and *l* is a centre cam. These three cams are fixed relative to the cam ring *f* and their upper surfaces are all in the same horizontal plane. Mounted in suitable guides on the cam ring *f* are slides *m* and *n*. Connected to slide *m* is a combined raising and stitch cam *o* and connected to slide *n* is a similar cam *p*. These slides *m* and *n* are each provided with a spring *q* for moving the slides toward the needle cylinder, and are also provided with adjustable screws *r* which engage one arm of a double bell crank lever *s*, which lever is pivoted in the bed *b*. The other arm of this bell crank lever is engaged by a pin *t* slidably mounted in the bed *b*. The pin *t* normally rests on the upper surface of disc *d* and is maintained to two higher positions by cam *e*, as hereinafter described.

Slidably mounted in the cylinder are three sets of latch needles which are the same in all respects, with the exception that the butts of each set differ in length from the butts of the other sets, as shown in Fig. 4, in which three needles are shown in three different horizontal planes. These needles coact with the usual sinkers to form stitches.

The yarn and needles are manipulated as illustrated in Figs. 8, 9 and 10 for knitting the first round to the loops of the top transferred to the needles.

In these figures, *u* designates the yarn clamp, *w* the yarn, *y* the yarn carrier, and *x* the sinkers. In this description the needles have been designated 1 to 108, with the assumption that there are one hundred and eight needles in the cylinder and in all of which the needles are viewed from the inside of the cylinder so as to show how they are manipulated by the cams shown in Fig. 3.

When a top is transferred to the machine to knit other portions thereto, all of the needles are in the plane of needles 1 to 8, as the butts of all of the needles have been shifted into a horizontal plane just above surfaces *g*, *g* of ring *f*. At this time cams *o* and *p* are withdrawn as shown in Fig. 5 with their slides *m* and *n* by a cam *e* on the cam disc, the high portion *e'* of which is under pin *t*.

After the top has been transferred to the machine, the loops of the top will so engage the needles as to prevent their latches from closing and casting the loops of the top without first raising the needles to clear the latches of the loops. The latch ring (not shown) is now thrown down into position about the needles and the machine is set into motion. Immediately after the machine is set into motion, the yarn carrier *y* is thrown into position to cast the yarn between needles 10 and 1, see Fig. 8. At this time, cam disc *d* is shifted to bring the cut-away portion *e²* of cam *e* under pin *t* to shift cams *o* and *p* into position to engage the long butts of the needles, as shown in Fig. 6, and as the needle cylinder is rotated counter-clockwise, cam *o* will act as a raising or latch clearing cam, while cam *p* will act as a stitch drawing cam. One half of the needles from 63 to 108, inclusive, and 1 to 8, inclusive, are provided with short butts, needles 9, 10 and 11 with medium length butts and needles 12 to 62, inclusive, with long butts; needles 17 to 106, inclusive, not being illustrated.

The cams *o* and *p* are shifted to the position shown in Fig. 6 (by reason of the pin *t* dropping from high portion *e'* onto the portion *e'* of cam *e*) prior to the time that cam *o* is reached by the first long butt needle 12, which raises the long butt needles to clear the latches. Immediately after needle 11 passes cam *o*, cam disc *d* will be shifted to move cam *e* out from under pin *t* and as cam *o* is under the long butt needles, its spring *q* will shift the cam to its regular knitting position. As the short butt needles have not passed the stitch cam *p* at this time, said cam will be shifted by its spring *q* against the short butts and as cam *p* is now positioned to engage the medium butts, needles 9, 10 and 11 will be drawn down by the stitch cam *p*, and as the loops trans-

ferred to these needles are between the hooks and the latches, the said loops as well as a supply of yarn will be drawn by these needles between their respective sinkers, while needle 12 (the first long butt needle) which was raised by cam *o* to clear its latch of the transferred loop will form the first stitch of the fabric by drawing yarn through the said transferred loop, while said transferred loop will be cast over the hook of needle 12 by the sinkers, see Figure 9. Needle 12 in its downward movement under the point of cam *p* will not only draw yarn from the supply through the yarn carrier *y*, but will draw or rob needle 11 of some of the yarn which it drew through the yarn carrier, as the said needle 11 is free to move up along the back of cam *p*. The stitch cam *p* will be moved into its extreme position by its spring *q* to engage the short butt needles after the last short butt needle has passed the cam. The first short butt needle after the last long butt needle (neither of which is shown) which I have designated as needle 62 as well as short butt needles 63 to 108 and needles 1 to 11 will now be raised successively to free their latches and to form their first loops, and the second round of knitting will be started on needle 12. Some of the stitches formed by the last needles to complete the first round of knitting, or the needles in advance of the long butts, will not only interknit the first round with the loops transferred to the said needles, but will also interknit the loose yarn thrown in front of those needles by the carrier *y* when first thrown into action. This will lock or interknit the beginning of the yarn forming the first loop on needle 12 with loops formed by needles 9, 10 and 11.

The manipulation of one or more needles in advance of the first needle to knit, to provide yarn to form the first loop, may be accomplished by other means known to the art, than that above described. For example, another way of forming the first stitch is illustrated in Figs. 11, 12 and 13.

In this form, needles 8' and 9' are short and long latched needles, respectively, and function the same as needles 8 and 9, of Figs. 8 to 10; that is, needle 8' does not draw yarn on the first round, while needle 9' having a long latch is the first needle to draw yarn.

Assuming that yarn is to be drawn by only one needle (needle 9') in advance of the first needle to knit, one half of the needles are provided with short butts while the other half are provided with long butts.

The first long butt needle is provided with a long latch, while all the other needles are provided with normal latches. When using this type of mechanism, the stitch cam

is the same as the cam p shown in Fig. 3, the successive following loops of the previously formed fabric, then drawing loops of yarn through the first mentioned loop or loops of the transferred fabric to complete the first round of interlooped fabric, and then successively drawing loops of yarn through the new loops as in regular knitting.

When starting to knit to the loops transferred to the needles with this form of mechanism, the yarn carrier is thrown into action to cast the yarn in front of a plurality of short butt needles, as in the other form. The needle actuating cams are then thrown into position to engage the long butt needles but not the short butt needles, and when in such position, the portion o^2 of cam o' is not in a position to engage the butts of any of the needles. As the needle cylinder is rotated after the cams have been shifted, the long butt needles will engage cam o' , which will raise all the long butt needles to a sufficient height to cause the latches of all of said needles to clear the loops thereon, with the exception of needle 9', the long latch needle. As needle 9' is not raised to clear its latch, it will not draw yarn through the loop thereon when passing under the stitch cam, but will draw yarn from the supply to furnish yarn for the next needle, which is the first needle to knit. After this needle passes the raising cam o' , the cams are thrown to their full knitting positions, and when so positioned the long butts, at least, will be engaged by portion o^2 of the raising cam to raise the needles to a height to clear all the latches of their loops, so that needle 9' will knit its first loop just before the first needle to knit forms its second loop.

As the first loop formed on needle 12 is formed in precisely the same manner as all other loops, by drawing yarn through the yarn carrier and by robbing yarn from the preceding needle which also drew yarn through the carrier and robbed its preceding needed, the first stitch must necessarily be of the same size and tension as the other loops.

The advantages of my invention result from the provision of a method for and means whereby the first stitch formed during the knitting of fabric to a previously formed piece of fabric is formed under the same conditions as the successive subsequent loops, so that the size and tension of the first knitted loops is substantially the same as subsequent loops and thereby avoid the making of seconds or menders.

Having now fully described my invention, what I claim and desire to protect by Letters Patent is—

1. The process of knitting tubular fabric to a previously knitted piece of tubular fabric, comprising transferring the previously knit fabric onto the needles of a circular bank of needles, drawing yarn from a supply and also drawing therewith one or more of the loops of the previously formed fabric without drawing said yarn through said loop or loops, then drawing the yarn through

the successive following loops of the previously formed fabric, then drawing loops of yarn through the first mentioned loop or loops of the transferred fabric to complete the first round of interlooped fabric, and then successively drawing loops of yarn through the new loops as in regular knitting.

2. The method of manipulating the needles of a circular machine to knit tubular fabric to a piece of tubular fabric transferred to said needles, comprising laying yarn in the hooks of one or more needles and drawing yarn therewith from the supply without forming loops by drawing such yarn through the loops on such needle or needles, laying the yarn in the hooks of the following needles in a successive manner and forming loops therewith by drawing the yarn through the loops transferred to the needles, then, after yarn has been delivered to the hooks of all of the needles, again delivering yarn to the hooks of the needles which were first supplied with yarn and now drawing the yarn through the transferred loops on the needles, and then drawing the yarn in a successive manner and order through the loops formed by said needles to complete the fabric.

3. In a machine for knitting fabric to a cuff transferred to the needles of said machine, comprising means for raising the needles to clear the latches of the loops transferred thereto, a yarn carrier for feeding yarn to the hooks of the needles, and means for lowering the needles to draw the yarn laid in the hooks of the needles through the loop transferred thereto, said needle manipulating means being arranged to lower at least one needle to draw yarn in advance of the first needle whose latch has cleared a loop of the transferred cuff.

4. In a machine for knitting fabric to a cuff transferred to the needles of said machine, comprising a cam device for raising the needles to clear the needle latches of loops thereon, a yarn carrier for feeding yarn to the hooks of the needles, cam means for lowering the needles to draw yarn through the yarn carrier and draw the needles through the loops thereon if the latches have been cleared, and means to manipulate the cams to cause one or more needles in advance of the first needle that draws yarn through a loop and whose latches have not been cleared, to draw yarn through the carrier so that the yarn on opposite sides of the first needle to knit is subjected to the same conditions as occur under normal knitting.

5. The process of knitting tubular fabric to a previously knit piece of tubular fabric, comprising transferring said previously knit fabric to the needles of a circular bank of needles, feeding yarn to the needles and

6
first drawing one or more unknit loops of the yarn without drawing yarn through the transferred loops and then successively drawing loops of the yarn through loops of 5 the previously knit tubular piece.

6. In a machine for knitting fabric to a cuff transferred to the needles of said machine, comprising means for raising the needles to clear the latches of the loops transferred thereto, a yarn carrier for feeding yarn to the hooks of the needles, and means for lowering the needles to draw the yarn laid in the hooks of the needles through the loops transferred thereto, said needle manipulating means being arranged to lower at least one needle to draw yarn in advance of the first needle whose latch has cleared a loop of the transferred cuff.

7. A machine for knitting tubular fabric 20 to a tubular fabric which has been transferred to a circular bank of needles, comprising said bank of needles, a source of yarn supply, means to operate the needles to cause them to successively draw yarn 25 from the supply through the loops of the transferred fabric and cast said loops, and means operative on the first round of knitting to prevent one or more of the first needles which draw yarn from the yarn supply after transferring from casting the loop 30 or loops on said needle or needles.

8. In a machine for knitting fabric to a cuff transferred to the needles of said machine, comprising a cam device for raising 35 the needles to clear the needle latches of loops thereon, a yarn carrier for feeding yarn to the hooks of the needles, cam means for lowering the needles to draw yarn through the yarn carrier and draw the needles through the loops thereon if the latches have been cleared, and means to manipulate 40 the cams to cause one or more needles in advance of the first needle that draws yarn through a loop and whose latches have not 45 been cleared, to draw yarn through the carrier so that the yarn on opposite sides of the first needle to knit is subjected to the same conditions as occur under normal knitting.

9. In a machine for knitting fabric to a 50 cuff transferred to the needles of said machine, comprising a cam device for raising the needles to clear the needle latches of loops thereon, a yarn carrier for feeding yarn to the hooks of the needles, cam means for 55 lowering the needles to draw yarn through the yarn carrier and draw the needles through the loops thereon if the latches have been cleared, and means to manipulate the cams to permit the first needle or needles 60 actuated by the cams after transferring to draw yarn with their hooks without freeing their latches of the transferred loops.

10. A circular knitting machine for knitting fabric to fabric transferred to the needles thereof, comprising means for deliver-

ing yarn to a predetermined number of needles in advance of the needle first manipulated to draw the yarn through a loop thereon, cams for manipulating said needles, and means for controlling said cams to cause them to actuate at least one of the needles to which the yarn is first delivered to draw yarn through the yarn delivery means without casting the stitches thereon and to cause the following needles to draw the yarn 75 through the loops thereon, cast the old loops and form new loops, so that loops drawn through the transferred loops by the needle first manipulated by the cams are formed on the second manipulation of said needles. 80

11. A circular knitting machine for knitting fabric to fabric transferred to the needles thereof, comprising a yarn carrier for delivering yarn to the needles, means for driving the machine, yarn carrier actuating connections between the pattern mechanism and the driving means, a needle raising cam, a stitch cam, and means under the control of the pattern mechanism to throw the yarn carrier and the cams into action to deliver the yarn to a plurality of needles in advance of the first needle actuated by the raising cam, the stitch cam being thrown into action to lower one or more needles to which yarn has been delivered but which have not been raised by the raising cam to draw yarn without drawing it through the loops on the needles, while the first needle which is raised by the raising cam draws the first loop formed by the needles through 95 the loop transferred thereto.

12. A circular knitting machine for knitting tubular fabric to a piece of knitted fabric transferred thereto, having a needle cylinder with needles mounted for reciprocation therein, means for leveling the needles into transferring position, a yarn carrier, a needle raising cam, a stitch cam, means for throwing the yarn carrier into action, means for throwing the cams into action, and controlling mechanism for said means for throwing the yarn carrier into action and for the means for throwing the cams into action for causing the raising cam to successively raise the needles, beginning with a predetermined needle to which yarn has been delivered to such a height that when the stitch cam lowers said needles, new loops will be drawn through the transferred loops on said needles, while the stitch cam is thrown into action to lower at least one needle in advance of the first needle raised by the raising cam to draw yarn through the yarn carrier and without drawing a new loop through the transferred loop on said 115 needle.

In testimony of which invention, I have hereunto set my hand, at Philadelphia, Pa., on this 27th day of April, 1922.

WILBUR L. HOUSEMAN.
